UNITED STATES PATENT OFFICE.

AARON L. DURN, OF RICHLAND, BUCKS COUNTY, PENNSYLVANIA.

CAR-COUPING.

SPECIFICATION forming part of Letters Patent No. 309,936, dated December 30, 1884.

Application filed September 11, 1884. (No model.)

To all whom it may concern:

Be it known that I, AARON L. DURN, of Rich-
land township, in the county of Bucks and
State of Pennsylvania, have invented certain
5 Improvements in Car-Couplings, of which the
following is a specification.

My invention relates to car-couplings; and
the invention consists in the novel construc-
tion, combination, and arrangement of devices
10 used, whereby the coupling and uncoupling
can be effected by a person on top of freight
or box cars, or platform of passenger-coaches,
and thereby avoid the accidents which so fre-
quently occur with the ordinary link-cou-
15 plings.

Figure 1 is a top plan view as attached to
the frame-work of box-cars; Fig. 2, a side view
as applied thereto, and Fig. 3 a transverse
vertical section.

20 In the drawings, A represents a combined
draw head and bar, which may be made of
wrought or cast iron, the head of which is
made arrow-shaped, with a slotted recess, a',
and pin-hole a, to provide for the coupling
25 with cars having the ordinary coupling link
and pin, and automatically as two cars come
in collision with the arrow-shaped heads by
passing each other, one over the other, where
they engage and are held by the points. The
30 draw-bar near the rear end is provided with
a hole transversely across, and through which
the bolt D passes, secured at both ends with
square or cubical shaped nuts or heads d,
bearing on the sliding bars B, secured to
35 frame-work of cars with bolts or otherwise,
thus allowing the draw-bar to turn loosely in
the line of its axis, which is essential in cou-
pling or uncoupling, or as may be required in
the application of my device to cars of vary-
40 ing heights to points of coupling. The draw-
bar A at its rear end or termination is flat-
tened out, and is provided with a slotted or
elongated hole, a'', cut vertically through it,
in which a spring-bolt, E, freely passes, around
45 which a spring-coil, e e, on each side of draw-
bar is made to bear against the same, holding
the draw head and bar in position or equi-
librium, and under the control by a series of
levers or other equally adapted mechanism,

to be moved upward or downward by a per- 50
son standing on the top of the car.

To relieve the draw head and bar from hav-
ing a rigid bearing, the spring-bolts b b on the
median line of the sliding bars B, the springs
bear against the sliding plate at one end of 55
the same and against the head of the bolts
at the other end, which in turn bears against
the nut and head of the bolt D, giving the
required elasticity to the draw head and bar.

C represents the bearing-plates for rock- 60
shaft H, and also provides a flange for retain-
ing bolts on the sliding bars in position, c c
serving a similar purpose on the opposite
sides of the sliding bars. A guide-bar, P,
(L-shaped,) is secured to platform or frame- 65
work near the draw-head to retain the same
in position.

To operate the draw-head from the top of
the car, a crank or lever arm, K, is employed
with a handle extending up above the roof of 70
car, the crank being secured to car by means
of bracket-arm L, and bolt M, and washer N,
the crank-handle being held in position by
means of a notched segmental plate, O, at-
tached to the car, and a spring-coil inserted 75
around bolt M bearing against crank-arm and
bracketed arm L. The crank or lever arm K
is connected with levers J and I, the rocking
shaft H and arm G, in suitable mountings,
conveying the motion from the handle and 80
crank-arm to the bolt E, operating on the
draw head and bar in raising or lowering the
head as desired.

I do not wish to limit myself to the above-
described method for operating the draw- 85
head, but would adapt mechanisms to effect
the same object for the different styles of cars
in use.

From the foregoing description the opera-
tion of my device will be readily understood. 90
To raise or lower the draw-head as required
in uncoupling the cars, the crank or lever arm
is disengaged from the notch by bearing
against and in the direction of the spring-bolt
on which it turns, and being moved to the 95
right or left, as required, for raising or lower-
ing the draw-head, which separates, and the
work of uncoupling is accomplished, after

which the handle is again brought to the proper notch in which the automatic coupling is effected as already described.

What I claim is—

- 5 1. The combination of the draw head and bar A, secured to the bolt D, spring-bolts b b, slide-bars B, and bearings C, &c., constructed and arranged substantially as shown and described.
- 10 2. In combination with the draw head and

bar A, the spring-bolt E, connected to arm G, rock-shaft H, lever-arms I and J, and crank K, or equivalent means for operating the draw-head, substantially as and for the purpose set forth.

AARON L. DURN.
